UNITED STATES PATENT OFFICE.

CECIL S. BUMANN, OF OAKLAND, CALIFORNIA, ASSIGNEE TO UNIT CONSTRUCTION COMPANY, OF ST. LOUIS, MISSOURI, A CORPORATION OF NEW JERSEY.

TRAIN-SHED.

1,231,998.

Specification of Letters Patent.

Patented July 3, 1917.

Application filed December 20, 1915. Serial No. 67,734.

To all whom it may concern:

Be it known that I, CECIL S. BUMANN, a citizen of the United States, and a resident of the city of Oakland, county of 5 Alameda, and State of California, have invented a new and useful Improvement in Train-Sheds, of which the following is a specification.

This invention relates to train sheds of 10 the umbrella type, and consists in a structure which is composed of reinforced concrete units which are molded at a convenient place, transported to the desired location, erected in position and secured together by 15 plastic concrete poured into suitable spaces left between the meeting edges of the units.

The invention further consists in the details of construction of the embodiment thereof which is shown in the accompanying 20 drawings, and is more particularly defined in the appended claims.

In the drawings, wherein the same reference characters are used to designate like parts in the several views,

25 Fig. 1 is a side elevation of a train shed embodying the invention, partly in section on the longitudinal center line of the structure;

30 Fig. 2 is a cross-section of the same on the line 2—2 in Fig. 1, looking in the direction of the arrows;

Fig. 3 is a plan view of a roof panel made in accordance with the invention;

35 Fig. 4 is a longitudinal cross-section of the panel shown in Fig. 3, on the line 4—4 in Fig. 3;

40 Figs. 5 and 6 are transverse cross-sections of the panel shown in Fig. 3 on the lines 5—5 and 6—6 in Fig. 3, respectively;

Fig. 7 is a face view of the top portion of a post;

Fig. 8 is a cross-section of the arm of the post shown in Fig. 7, on the line 8—8 in Fig. 7; and

45 Fig. 9 is a cross-section of a batten strip.

The drawings show a single platform 11, between two tracks 12; but it is understood that there are usually several parallel platforms spaced apart with either one or two 50 tracks intervening between adjacent platforms. The platforms may be made of concrete, brick, or any suitable material, and are usually from twelve to twenty feet wide.

Along the middle of each platform is a 55 row of reinforced concrete posts 13, spaced

about twenty to twenty-five feet apart. These posts are T-shaped, with their two arms 14 spreading out crosswise of the platform and reaching from about one-half to two-thirds of the way across it. The lower 60 ends of the posts are set in sockets in concrete pedestals 15 beneath the platform, and after being lined up properly the posts are rigidly secured in place by pouring grout around their lower ends to fill the spaces 65 between them and the walls of the sockets. Angle irons 16 are cast on the corners of the posts, extending for a distance of about four feet above the platform to protect the posts from accidental injury by contact with 70 trucks, baggage, or other objects on the platform. The arms 14 are wider than the posts, and have ledges or notches 17 along their two top edges in which the ends of the roof slabs 18 are laid. These ledges have 75 a slight slope upward and outward from the midline of the platform.

The roof slabs 18 are made of reinforced concrete, and are arranged in pairs between the posts, there being a roof slab on each 80 side of the longitudinal center line of the structure extending from each post to the next. The inner edges of the roof slabs of each pair abut, and their outer edges project beyond the edges of the platform. Each 85 roof slab has two longitudinal girders 19 running from end to end, and connected at their ends by cross girders 20. One longitudinal girder is at the inner edge of the slab, and is provided with a longitudinal 90 groove 21 in its side adjacent to the mating roof slab. The grooves 21 of each pair of girders register with each other and form a channel into which grout is poured to key the two roof panels together lengthwise to 95 hold their inner edges in the same horizontal plane. The outer longitudinal girder of each roof slab is located in alinement with the ends of the ledges or notches 17 of the supporting arms.

100 The outer portions 22 of the roof slabs slope upward and outward from the outer girders 19, and are braced by cross ribs 23 spaced every few feet apart lengthwise of the slab. These cross ribs 23 extend across 105 the panel to the inner girders and stiffen the middle portion of the slab. The ends of the outer overhanging margins 23 of the roof slabs project lengthwise of the structure beyond the ends of the girders and middle 110

portions of the slabs and meet opposite middle points of the ends of the arms 14. The spaces between the meeting ends of the slabs are filled with grout, and the spaces between the slabs and the arms 14 are grouted likewise; and likewise the space over each arm between the ends of the middle portions of the roof slabs is filled with grout. Batten strips 24 of concrete are arranged beneath and at the ends of the joints between the ends of the outer margins 23 of the roof slabs. These battens are held in place by short wires 25 which are looped into the battens, the upper ends of which project into the spaces between the ends of the roof slabs and are embedded in the grout.

The posts 13 are each reinforced by four rods 26, arranged one in each corner, extending from top to bottom, and by loops 27 encircling the rods 26 and spaced about a foot apart for the entire length of the post. The curved rods 28 follow the lower face of each curved bracket into the lower part of the arms 14 at their ends. The arms 14 are also reinforced by two straight rods 29 in the bottom region and four straight rods 30 in the top region extending from end to end, and one straight rod 31 in the upper portion of each side ledge. Vertical stirrups 32 surround the longitudinal rods in the arms and tie in the rods 31, these stirrups being spaced every few inches apart near the ends of the arms, the spacing increasing to a foot or so apart at the middle. The ends of the straight rods in the lower region of each arm are bent up parallel with the ends of the arms, and the ends of the straight rods in the tops of the arms are hooked under them.

The roof slabs are each reinforced by four straight bars 33 spaced lengthwise in the top of the main portion of the slab. The beams 19 are reinforced by straight bars 34 arranged lengthwise in their bottoms, and by bent bars 35 arranged in the bottom region at the middle of the slab and in the top region at their ends. The crosswise ribs 23 are each reinforced by two bars 36, which are arranged in the top region of the ribs at their outer ends, and cross into the bottom region of the ribs at their inner ends, as shown in Fig. 6. These ribs are also reinforced by vertical stirrups 37, spaced about a foot apart lengthwise of the ribs from side to side of the slab. These stirrups are hooked over the straight bars running lengthwise of the slab where they are in juxtaposition, as shown in Fig. 4.

The overhanging portion 22 of the slab is reinforced by two series of parallel bars, straight bars 38 in the bottom of the slab alternating with bent bars 39, which lie in the bottom of the slab between the ribs

23 and in the top of the slab across the ribs. Crosswise bars 40 extend from edge to edge of the slab in the bottom at intervals of two feet or so, and bent bars 41 are arranged across the main portion of the slab between the bars 40. Across the middle of the slab the bars 41 are in the bottom, and near the beams 19 they are in the top. The ends of the bars 41 are bent over the outer straight bars 23 and down into the bottoms of the beams, across the bottoms, and up the inner sides of the beams to their tops, forming stirrups 42. Additional stirrups 43, similar to the stirrups 42, are provided near the ends of the beams 19 and in the end beams 20. The end cross beams 20 are reinforced and tied into the roof slabs by bars 44 in the top and bottom, respectively. The bars 44 are straight, with their ends bent at right angles and extending into the ends of the longitudinal beams 19. Short straight bars 45 are arranged over the ends of the straight bars 38 in the ends of the overhanging portions of the slabs.

Suitable ducts are provided for conducting rain water from the middle of the roof, and the roof panels are inclined upwardly and outwardly from the middle to cause rain water to flow inwardly from the edges, as in a gutter, and keep it from dripping off the eaves.

It is evident that changes in the form and dimensions of the parts can be made without departing from the invention; and the invention is not restricted to the forms and dimensions shown and described.

I claim the following as my invention:

1. A train shed comprising spaced posts having cross arms at their upper ends, and unitary roof panels extending from post to post and resting on said arms, said roof panels having a greater spread than said cross arms, and their outer projecting portions abutting opposite the ends of said cross arms, and battens arranged beneath said abutting ends.

2. A train shed comprising spaced posts having cross arms at their upper ends, and unitary roof panels extending from post to post and resting on said arms, said roof panels having a greater spread than said cross arms, and their outer projecting portions abutting opposite the ends of said cross arms, and battens arranged beneath said abutting ends, said battens being secured in place by ties embedded therein having their ends projecting up into the spaces between said abutting ends and embedded in plastic material in said spaces.

3. In a train shed, in combination with spaced posts having cross arms, reinforced concrete roof panels resting at their ends on said cross arms, said roof panels being arranged in pairs on opposite sides of the longitudinal center line of the structure, the in-

ner margins of the panels of each pair being keyed together and outer margins of said roof panels overhanging the ends of said arms and being supported by cantalivers 5 from the inner margins thereof.

4. In a train shed, in combination with spaced posts having cross arms, reinforced concrete roof panels resting at their ends on said cross arms, said roof panels being arranged in pairs on opposite sides of the longitudinal center line of the structure, the inner margins of the panels of each pair being

keyed together and outer margins of said roof panels overhanging the ends of said arms and being supported by cantalivers 15 from the inner margins thereof, said roof panels having crosswise reinforcement in the top region and lengthwise reinforcement in the bottom region of said overhanging outer margins.

Signed at San Francisco, Cal. this 13th day of December, 1915. 20

CECIL S. BUMANN.
